ADJUSTING MECHANISM FOR MASTER COPIES ON DUPLICATING MACHINES AND THE LIKE

Mustafa J. Ajam, Amherst, N. H., and Joseph R. Paradis, Malden, and Carl A. Bergman, Melrose, Mass., assignors to Standard Duplicating Machines Corporation, Everett, Mass., a corporation of Massachusetts

Application October 4, 1950, Serial No. 188,392

4 Claims. (Cl. 101—248)

1

The present invention relates to mechanism for adjusting the position of the master copy used on fluid duplicating machines with respect to the position of the printing on the clear sheet on which the copy is reproduced.

As fluid duplicating machines are used for more and more purposes, perfect registration of the printing on the clear sheet has become more and more important; also the ability to adjust the position quickly and with great accuracy. The importance of this can be illustrated by considering a particular case. For instance, if a price-list has already been printed with blank spaces for prices opposite particular items, the blank spaces may be filled in by a duplicating machine. Often some price figures are added after others have been put in. Unless each price figure is placed precisely in line with the item to which it applies, a person receiving the price-list may mistake the price of the item, and confusion or even loss may result. Also, it is important that the operator of the duplicating machine shall be able to correct any misalignment instantly and accurately upon examining the first or second copy which is made by the machine. Since such copies are frequently made in a hurry, it is essential that the necessary adjustment should be capable of being made instantly, certainly and without effort.

The mechanism embodying the present invention provides simple easily operated mechanism for moving the printing up or down on the clear sheet so that it will fall in precisely the desired position, particularly with relation to other printing which may be on the clear sheet already. This result is achieved by shifting the driven gear on the platen or drum shaft angularly of the drum by means of a thumb wheel located at the end of the drum in position to be under the thumb of the operator when the drum is in the normal stopping position.

The invention will be fully understood from the following description taken in connection with the accompanying drawings, in which:

Fig. 1 is a plan view of a drum or platen of a fluid duplicating machine embodying our invention, the drum being shown as broken away to show the mechanism;

Fig. 2 is a view of the left-hand end of the parts shown in Fig. 1; and

Fig. 3 is a detail of the adjusting mechanism separated from the other parts.

Referring now to the drawings, the drum is indicated at 11, the shaft at 12, and the driven gear at 13. It will be understood that the gear

2

13 is movable angularly of the drum 11 and that such movement changes the angular position of the drum with respect to the position of the feed rolls (not shown) and consequently varies the position of the clear sheet with respect to the master copy by advancing or retarding the time when the front edge of the clear sheet arrives at the bite of the pressure roll and the drum, all as has been explained in the patent to Storck 10 Reissue No. 19,951.

The drum 11 is provided with an indicating mark 40 adjacent scale 41 on the frame 42 of the machine. This scale is conveniently calibrated to indicate lines of type as printed by a 15 standard typewriter. The present invention provides mechanism for making this angular adjustment more easily, quickly and accurately.

At 14 is shown a stud having a body 15 and a screw-threaded bore therein. The stud 14 is received in a hole in the spoke 17 of gear 13 and can rotate slightly as the adjustment takes place. A screw shaft 19 is received within the screw-threaded bore of the body 15 of the stud 14, and has a bevel gear 20 thereon. The screw shaft 19 25 passes through the arms 22 and 23 of a yoke 24 which is pivoted on the end of a shaft 27 which extends lengthwise of the drum 11 and is rotatable in the spokes 26, 26 forming part of the ends of the drum. This shaft 27 has at one end a bevel gear 28 which meshes with the bevel gear 20 and on the other end a thumb wheel 30 whose knurled periphery extends through a hole 31 cut in the end edge of the drum sufficiently to allow the operator to turn the wheel 30 by his thumb. The end of the screw-shaft 19 extends beyond 35 the gear 20 into a bearing in the arm 23 of the yoke 24.

After the operator has run a sheet or two through the machine and inspected to see 40 whether the printing is properly positioned up or down on the sheet, the thumb wheel 30 may be turned in the proper direction to adjust the printing up or down to the correct position. Moving the thumb wheel 30 turns the shaft 27 and the bevel gear 28 which in turn rotates the bevel gear 20 and the screw shaft 19. This 45 pulls or pushes the body 15 of the stud 14 toward or away from the yoke 24. Since the yoke 24 is carried by the drum 11 and the stud 14 by the driven gear 13, this changes the angular 50 relation of the drum and gear and consequently moves the position of the master copy up or down with relation to the copy sheet. The position of the thumb-wheel on the top of the drum enables the operator to make the adjust-

ment easily and quickly, and in the machine shown herein, movement of the indicator mark 40 one space on scale 41 shifts the master copy up or down, as the case may be, one line. Of course, it will be understood that the drum may be moved more or less than the amount of one line to improve the alinement of the work on the copy sheet as may be required.

We claim:

1. In a liquid duplicating machine or the like and in combination with a drum and a driven gear therefor coaxial with the drum the means for shifting the drum and the gear angularly with respect to each other which comprises a stud in engagement with the driven gear, a screw shaft threadedly engaging the stud, a bevel gear on said screw shaft, a shaft carried by the drum, a yoke having bearings for the screw shaft and being pivotally mounted on the drum and to support the screw shaft for pivotal movement relative to the drum and provided with a bearing for the shaft on the drum, a second bevel gear on the said shaft and engaging the first mentioned bevel gear, and a thumb wheel on the shaft carried by the drum.

2. In a liquid duplicating machine or the like and in combination with a frame, a drum having a cut-out place in the edge of the drum adjacent the frame of the machine and a driven gear therefor coaxial with the drum the means for shifting the drum and the gear angularly with respect to each other which comprises a stud in engagement with the driven gear, a screw shaft threadedly engaging the stud, a bevel gear on said screw shaft, a shaft carried by the drum, a yoke having bearings for the screw shaft and being pivotally mounted on the drum to support the screw shaft for pivotal movement relative to the drum and provided with a bearing for the shaft on the drum, a second bevel gear on the said shaft and engaging the first mentioned bevel gear, and a thumb wheel on the shaft carried by the drum and located in said cut-out place in the edge of the drum.

3. In a liquid duplicating machine or the like and in combination with a frame, a drum having a cut-out place in the edge of the drum adjacent the frame of the machine and having an indicating mark at the edge of the drum and a driven gear therefor coaxial with the drum the means for shifting the drum and the gear angularly with respect to each other which comprises a stud in engagement with the driven gear,

a screw shaft threadedly engaging the stud, a bevel gear on said screw shaft, a shaft carried by the drum, a yoke having bearings for the screw shaft and being pivotally mounted on the drum to support the screw shaft for pivotal movement relative to the drum and provided with a bearing for the shaft on the drum, a second bevel gear on the said shaft and engaging the first mentioned bevel gear, and a thumb wheel on the shaft carried by the drum and located in said cut-out place in the edge of the drum, the frame of the machine having a scale thereon adjacent the indicating mark on the drum.

4. In a liquid duplicating machine or the like having in combination a frame, a drum having a cut-out place in the edge of the drum adjacent the frame of the machine, indicating marks at one edge of the drum, corresponding indicating marks on the frame adjacent one edge of the drum, a driven gear coaxial with the drum and having a hole in the side thereof, means for shifting the drum and gear angularly with respect to each other, including a stud received in and rotatable in said hole, a screw shaft threadedly engaging the stud, said screw shaft being supported in a yoke, said yoke being pivotally mounted inside the drum to support the screw shaft for pivotal movement relative to the drum, a bevel gear on said screw shaft, a shaft carried by the drum having one end journaled in said yoke and extending longitudinally inside the drum, a bevel gear at one end of the shaft carried by the drum and in engagement with the bevel gear on the screw shaft and a thumb wheel on the shaft carried by the drum located in said cut-out place in the edge of the drum.
